[57] **CLAIM**

The ornamental design for a fishing game board, as shown and described.

DESCRIPTION

FIG. 1 is a plan view of a fishing game board, showing my new design.

FIG. 2 is an enlarged fragmentary view of the top portion of the fishing game board disclosed in FIG. 1.

FIG. 3 is an enlarged fragmentary view of the bottom portion of the fishing game board disclosed in FIG. 1. The drawing is lined for color.

FIG. 1

FIG. 3
